(57) **CLAIM**

The ornamental design for a plant grow light, as shown and described.

DESCRIPTION

FIG. 1 is a front perspective view of a plant grow light, showing our new design in a retracted position;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is a front perspective view of the plant grow light of FIGS. 1-8, but shown in an extended position.

The figures include surface shading, which represents contour and not surface ornamentation.

The uniform broken lines shown in the figures illustrate portions of the plant grow light that form no part of the claimed design.
